UNITED STATES PATENT OFFICE

154,454

DESIGN FOR A COLLAPSING WHISK BROOM

Walter R. Amstutz, Chicago, Ill., assignor to Butler Brothers, Chicago, Ill., a corporation of Illinois

Application June 7, 1947, Serial No. 139,521

Term of patent 14 years

(Cl. D9—2)

To all whom it may concern:

Be it known that I, Walter R. Amstutz, a citizen of the United States and a resident of Chicago, in the county of Cook and State of Illinois, have invented a new, original, and ornamental Design for a Collapsing Whisk Broom, of which the following is a specification, reference being had to the accompanying drawing, forming part thereof.

Figure 1 is a perspective view of a collapsing whisk broom showing my new design with the broom portion extended.

Figure 2 is a perspective view thereof with the broom portion retracted.

Figure 3 is a plan elevational view of Figure 1, and

Figure 4 is a side elevational view thereof.

I claim:

The ornamental design for a collapsing whisk broom, substantially as shown.

WALTER R. AMSTUTZ.
